UNITED STATES PATENT OFFICE

2,497,878
SEALING AND LEVELING MEANS FOR
LIFTER ROOF TANKS

Edward S. Fraser, Chicago, Ill., assignor to Chicago Bridge & Iron Company, a corporation of Illinois

Application May 31, 1946, Serial No. 673,676

8 Claims. (Cl. 48—176)

This invention relates to a lifter roof tank comprising a shell and a lifter roof thereover, and relates particularly to a sealing and leveling means for such a tank.

Lifter roof tanks are designed for the storage of gas and mixtures of liquid and gas. In these tanks the roof rises and falls as the pressure of gas within the tank is increased and decreased. It is necessary that a sealing means be provided to seal the area between the roof and the shell of the tank and that stabilizing and leveling means also be provided to maintain the roof substantially level at all times. In the present invention the sealing and leveling means have been combined so as to produce a simpler and more satisfactory construction.

The present invention broadly comprises a trough of substantial depth at the top of the shell, a depending hollow compartment attached to the roof and extending into the trough, and a liquid substantially filling the trough when the roof is in its lowest position, with the compartment being immersed in the liquid.

The invention will be described as related to the embodiments shown in the accompanying drawings. Of the drawings, Fig. 1 is a fragmentary plan view of a lifter roof tank embodying the invention; Fig. 2 is a vertical section taken along line 2—2 of Fig. 1; Fig. 3 is a vertical section similar to Fig. 2 showing an alternate embodiment of the invention; Fig. 4 is a view similar to Fig. 2 showing another embodiment of the invention; Fig. 5 is a view similar to Fig. 2 showing still another embodiment of the invention; and Fig. 6 is a view similar to Fig. 2 showing another embodiment of the invention.

In the embodiments shown in the accompanying drawings the lifter roof tank comprises a shell 10, a lifter roof 11 thereover having a depending skirt 12 attached to the edge of the lifter roof 11 beyond the shell 10. In the embodiment shown in Figs. 1 and 2 there is provided a trough 13 at the top of the shell supported on brackets 14 and having substantially parallel sides 15. Inner 16 and outer 17 angle irons are provided at the top of the trough in order to give the sides stability. A depending hollow compartment 18 is attached to the roof and extends down into the trough 13. This compartment may be continuous around the roof, or may be made in sections divided by transverse bulkheads. A liquid 19 is provided within the trough 13 and substantially fills the trough when the roof is in its lowest position as shown in Fig. 2. The hollow compartment 18 is fluid-tight for at least that portion 55

2 which is immersed in the liquid. The compartment may, however, have an opening to the atmosphere at a point above the liquid level. There is also provided a drip bar 20 on the bottom surface of the lifter roof 12, with this drip bar being located inwardly from the trough 15 so that vapors condensing on the bottom surface of the roof will not fall into the trough, but will drip back into the shell of the tank. There is also provided an angle iron 21 around the bottom of the skirt 12 in order to give the skirt rigidity.

The compartment 18 and the liquid 19 provide a seal to prevent the escape of vapors from within the tank. The compartment will also resist 15 any tendency of the roof to leave a horizontal position. The weight of the roof overcomes the buoyancy of the compartment and gas pressure within the tank is required to raise the roof.

The usual safety valves and other devices may 20 be provided on the tank. Guide means may also be provided to cause the roof to move in a substantially vertical path only and to prevent rotation of the roof.

In the embodiment shown in Fig. 3 the compartment 18a is provided with a plurality of passages 22 extending through the compartment near the bottom thereof. These passages are designed to vent vapor from the tank when the roof rises to a predetermined height and to prevent raising the bottom of the compartment out of the liquid. There is also shown a drip trough 23 attached to the inner surface of the compartment to catch the condensate forming on the bottom surface of the roof 11. A pipe 24 conveys this condensate back into the tank. The trough 15a is here shown located beyond the shell 10 and supported on brackets 14a. In this embodiment there is also provided a flexible sealing member 25 extending from the top outer edge of the trough to the skirt 12. This sealing member serves to seal the area between the trough and the skirt.

In the embodiment shown in Fig. 4 the sides 15b of the trough slope outwardly from the bottom to the top of the trough. This construction 45 serves to decrease the effect of the receding liquid level as the roof rises because the top of the trough has a larger cross sectional area than has the bottom.

In the embodiment shown in Fig. 5 the trough 50 is provided with an enlarged section 26 at the top of the trough so as to make the cross-sectional area larger at this point. This construction also serves to decrease the effect of the receding liquid level as the roof rises. The bottom surface 27 of the enlarged section 26 is preferably located

at substantially the lowest liquid level within the trough when the roof has reached the highest point of its travel.

The embodiment shown in Fig. 6 is similar to the embodiment shown in Fig. 2, except that here the trough 13 is provided with a plurality of substantially horizontal downwardly extending pipes 28 also filled with liquid 19a. Each pipe 28 has a smaller pipe 29 located within it with the smaller pipe attached to the bottom of the compartment 18. Each pair of pipes 28 and 29 is substantially concentric with the outer pipe being sealed at the bottom as by plate 30. The inner pipe 29 is sealed at the connection to the compartment, but may be either opened or closed at the bottom. As shown, the inner pipe is closed by a closure plate 31. Any number of these concentric pipes may be placed around the tank. These sets of concentric pipes serve to dampen out any tendency for the roof to set up an oscillating up-and-down movement. The dampening is caused by the small area through which the liquid must flow between the concentric pipes. The concentric pipes also serve to prevent any rotational movement of the roof.

Having described my invention as related to the embodiments set out in the accompanying drawings it is my intention that the invention be not limited by any of the details of description unless otherwise specified, but rather be construed broadly within its spirit and scope as set out in the accompanying claims.

I claim:

1. In a lifter roof tank comprising a shell and a lifter roof thereover, sealing and leveling means comprising an annular trough of substantial depth at the top of the shell and adapted to contain a sealing liquid, an annular depending hollow airtight compartment attached to the roof and extending into the trough whereby the liquid substantially fills the trough when the roof is in its lowest position and buoys up the depending compartment which is immersed therein.

2. The sealing and leveling means of claim 1 wherein the trough is larger in horizontal cross-section at the top than it is at the bottom.

3. The sealing and leveling means of claim 1 wherein the trough has at least one side sloping upwardly and outwardly so as to be larger in horizontal cross-section at the top than it is at the bottom.

4. The sealing and leveling means of claim 1 wherein the trough is provided with substantially parallel sides with one side having its top portion offset to provide a larger cross-section at the top of the trough than at the bottom, whereby the liquid level is maintained at substantially the

bottom of the offset portion when the roof is in its highest position.

5. The sealing and leveling means of claim 1 wherein the trough is provided with substantially vertical wells extending downwardly from the bottom thereof, said wells being also adapted to be filled with the liquid and the compartment is provided with downwardly depending hollow fluid-tight posts adapted to telescope in said wells, the inner dimensions of each well being slightly larger than the corresponding outer dimensions of its post.

6. The sealing and leveling means of claim 1 wherein the compartment is provided with spaced passageways near the bottom thereof extending from side to side of the compartment.

7. In a lifter roof tank comprising a shell, a lifter roof thereover, and a downwardly-extending skirt attached to the edge of the roof and located beyond the shell, sealing and leveling means comprising an annular trough of substantial depth at the top of the shell and adapted to contain a sealing liquid, an annular depending hollow airtight compartment attached to the roof and extending into the trough, said compartment being adapted to be buoyed up by liquid in the trough when the roof is in its lowest position, and a flexible member attached to the outer side of the trough and pressing against the inner surface of the roof skirt, said flexible member extending around substantially the entire circumference of the tank so as to seal the area between the shell and the roof skirt.

8. In a lifter roof tank comprising a shell and a lifter roof thereover, sealing and leveling means comprising an annular trough of substantial depth at the top of the shell and having side-walls extending from top to bottom of the trough, said trough being adapted to contain a sealing liquid, an annular depending hollow airtight compartment attached to the roof and having sidewalls extending into the trough whereby the liquid substantially fills the trough when the roof is in its lowest position and buoys up the depending compartment which is immersed therein, at least one of said sidewalls being inclined from the vertical.

EDWARD S. FRASER.
